UNITED STATES PATENT OFFICE.

CHRISTIAN REINKER, OF LAKWOOD, OHIO.

GEAR-REMOVER OR PINION-PULLER.

1,352,990.

Specification of Letters Patent. Patented Sept. 14, 1920.

Application filed December 27, 1918. Serial No. 268,541.

To all whom it may concern:

Be it known that I, CHRISTIAN REINKER, a citizen of the United States, residing at Lakewood, in the county of Cuyahoga and 5 State of Ohio, have invented certain new and useful Improvements in Gear-Removers or Pinion-Pullers, of which the following is a specification.

My invention relates to a gear remover or 10 pinion puller comprising a means for gripping a gear or pinion and means connected therewith adapted to engage a shaft and exert a powerful pull, whereby a gear may be easily and quickly removed from a shaft, 15 for example, a gear fixed on the end of an armature shaft, all without injury to the gear and shaft or any bearing part thereof. The device is of especial utility in electric car repair shops where it is a daily occurrence and necessity to remove the gears from 20 armatures. Ordinarily this is a difficult and lengthy operation and frequently damaging to the armature or bearing parts thereof, but with my invention the work is speedily 25 and safely accomplished.

In the accompanying drawing, Figure 1 is a longitudinal section of the device in grappling position upon a gear. Fig. 2 is an end view of the device, and Fig. 3 a side 30 view thereof. Fig. 4 is a perspective view of one of the grappling members.

In detail, the device consists of a heavy metal plate 2 which is round and notched at uniform distances radially at its edge to 35 receive the T-shaped shanks 3 of separate grappling hooks or members 4. A band 5 is removably affixed upon the plate by screws, and the grappling members are thereby loosely held in place. Each member 4 is 40 rounded transversely and provided with a hook end or flange 6 which is also rounded or of segmental form and wider than the shank end of the member. The outer or free 45 end of each member is also beveled at its outer rounded side, or in other words of wedge shape, and an interchangeable loose ring 7 encircles the several grappling members to lock them on any given sized gear when slipped over such wedge ends. When 50 the ring is slipped in the other direction each and all of the members may be spread outward to the limit afforded by their loose connection with plate 2. To complete the device, a heavy screw 8 with a square screw 55 thread extends through the center of the plate, and this screw has a square or angular

end 9 adapted to be engaged by a wrench to turn the same. The plate is also preferably provided with a square hub or extension 11 for wrench engagement also, although an integral arm or handle might be used in lieu of the wrench so that in turning the screw suitable resistance may be offered to prevent the plate from turning. Ordinarily, a wrench five to six feet long is required to turn the screw when the device is engaged with a gear, and this length of lever indicates the power required to remove a gear. Different sized rings 7 are used for 60 different sized gears.

In use, the grappling members are spread apart and slipped over the end of the gear 14 until the hook ends are adapted to engage behind the end faces of the teeth of the gear and then the locking ring is pressed outward 70 over the wedge portions of the members to force the hook ends into interlocking engagement with the gear. The inner end of the screw is thus placed opposite the end of the armature shaft 15 and when turned by 75 a long wrench as stated the screw will press against the end of the shaft and exert a powerful pull on the grappling members and gear; and in action, the gear if exceptionally tight on the shaft will resist the pull 80 until it flies off. There is no engagement or pressure on the bearing part of the shaft or armature and notwithstanding the power exerted and applied as stated no injury occurs to either the gear or the armature parts. 85

What I claim is:

1. A gear remover, comprising a notched plate, a set of beveled grappling members having headed ends loosely engaged within the notches of said plate, a slip ring engaging the beveled portions of said grappling members, and a screw extending centrally through the plate.

2. A device for removing a gear from a shaft, comprising a notched plate, a series 100 of grappling hooks having T shanks loosely connected with said plate, a locking ring encircling said grappling hooks, and a screw extending centrally through said plate.

3. A device for removing a gear from a 105 shaft, comprising a set of grappling members, a slip ring surrounding said members, a mounting for said members having a central angular projection to hold it from turning, and a screw extending through said projection and having means adapted to effect rotation thereof.

4. A device for removing a gear from a shaft, consisting of a round plate having notches in its edge and a wrench-engaging extension at one side, a set of grappling members seated having T-shaped shanks loosely seated within said notches, a band about said plate and members and means to secure said band removably in place, and a screw extending centrally through said plate.

5. A device for removing a gear from a

shaft, comprising a plate having an angular extension adapted to receive a wrench, a screw extending through said plate having a wrench engaging end, a set of grappling hooks and a movable band adapted to hold the same loosely connected with said plate, and a locking ring encircling said members.

Signed at Cleveland, in the county of Cuyahoga, and State of Ohio, this 14th day of December, 1918.

CHRISTIAN REINKER.
